UNITED STATES PATENT OFFICE

139,079

DESIGN FOR A WALL PLAQUE UNIT

Otto G. Dallmann, St. Cloud, Minn.

Application July 3, 1944, Serial No. 114,285

Term of patent 14 years

(Cl. D29—23)

To all whom it may concern:

Be it known that I, Otto G. Dallmann, a citizen of the United States, residing at St. Cloud, in the county of Stearns and State of Minnesota, have invented a new, original, and ornamental Design for Wall Plaque Unit, of which the following is a specification, reference being had to the accompanying drawing, forming a part thereof, and in which

I claim:

The ornamental design for a wall plaque unit, substantially as shown.

OTTO G. DALLMANN.
